UNITED STATES PATENT OFFICE.

JEREMY RUSSELL TOTMAN, OF COLUSA, CALIFORNIA.

MACHINE FOR SOUNDING DANGER SIGNALS.

Application filed May 15, 1922. Serial No. 561,176.

To all whom it may concern:

Be it known that I, JEREMY RUSSELL TOTMAN, a citizen of the United States, residing at Colusa, in the county of Colusa 5 and State of California, have invented a new and useful Machine for Sounding Danger Signals, of which the following is a specification.

My invention relates to improvements in 10 danger signal machines in which hammers are rapidly pushed back and released; said hammers, when released, being pulled forward by springs until they strike a bell or gong, and provided with cushions which 15 hold them on the rebound, so that the bell or gong may vibrate; said machine being operated by an electric motor which may be started at the main telephone office, or other convenient point; and the objects of 20 my improvement are, first, to provide an efficient alarm in case of fire, or for other purpose where an alarm would be needed; and, second, to provide for starting said alarm at any convenient point.

25 I attain these objects by the mechanism illustrated in the accompanying drawing, in which—

Figure 1 is a front view, showing the improvement proper; Fig. 2, a side elevation 30 with one standard L L, Figs. 1 and 3, removed, and Fig. 3, a back view, showing how the motor is attached.

Similar letters refer to similar parts throughout the several views.

35 The machine is attached to a framework Z, the bell or gong being attached above.

The hammers A A, with handles C C, which contain openings, as at X, Fig. 2, for the reception of notched push-bars D D, and 40 the release planes E E, supported by the standards L L; also the rocking arm F, to which the connecting rod G, and push-bars D D, are attached; also the coil springs H H, and cushions I I, constitute the main 45 parts of my improvement.

When crank J, is started it pulls connecting rod G, which oscillates rocking arm F. This causes push-bars D D, to be moved back and forth.

50 When push-bar D, on the right, is thrown far enough to the left, it engages hammer handle C, on the right, by the notch Y, falling into opening X, shown in Fig. 2. Push-bar D, thus engaged, pushes hammer handle C, with hammer A, on the right, back until the end of push-bar D, comes in

contact with inclined plane E, when it is raised, thus releasing hammer handle C, with its hammer A.

When hammer A, is released, it is pulled 60 back by spring H, and strikes bell or gong B, and is caught and held on its rebound by cushion I. As hammer A, on the right, is being released, push-bar D, on the left, is engaging hammer handle C, on the left. 65 It in turn is pushed back and released in the same manner as that just described.

When motor M, Fig. 3, is started by switching on the electric current at any convenient point, it turns pinion P, which is 70 connected with cog wheel N. Cog wheel N, is connected with worm reducing gear W, Fig. 3, by shaft S.

Worm reducing gear W, turns cog wheel O, and cog wheel O, transmits motion to 75 shaft V, to which crank J, is attached. Standards U U, Fig. 2, support shaft V, and thrust collars T T, hold shaft V, in place longitudinally. Standards Q Q, Fig. 3, support shaft S, and thrust collars R R, 80 keep shaft S, from moving longitudinally.

There may be one or more hammers.

I am aware that prior to my invention danger signal machines have been made on a small scale with electrically driven hammers. I therefore do not claim such a combination broadly; but

I claim:

The combination in a danger signal machine of a rocking arm, two hammers with 90 handles, each handle being fastened at the end so as to swing freely, two push-bars attached to said rocking arm, which alternately engage and disengage said hammer handles, and means for driving said push-bars backwards and forwards, said push-bars passing through a slit in said hammer handles near the middle and engaging them by means of a notch cut into the under side of said push-bars which fall by gravity 95 when in the proper position so that said notch catches at the lower end of said slit on said hammer handles, said push-bars being disengaged from said hammer handles by their ends coming in contact with inclined planes at their extreme outward thrust, which causes them to be raised, thus allowing said hammer handles with 100 their hammers to be freed and swing back, said hammers on said backward swing striking a bell or gong, substantially as set forth.

105

JEREMY RUSSELL TOTMAN.
